UNITED STATES PATENT OFFICE

HUGH A. STOUT, OF SHAWNEE, OKLAHOMA

COMBINED DISPLAY AND STORAGE DEVICE

Application filed August 26, 1929. Serial No. 388,576.

This invention relates to a rotatable, refrigerated, horizontally disposed, combined display and storage device designed primarily for use for displaying, storing and selling of candy, but it is to be understood that a device, in accordance with this invention may be employed in any connection for which it may be found applicable, and the invention has for its object to provide, in a manner as hereinafter set forth, a rotatably supported, horizontally disposed element having a refrigerant compartment surrounded by a series of readily accessible storage compartments for the reception of different articles of merchandise to be dispensed therefrom, and with each storage compartment including means for maintaining in spaced relation to the articles stored therein similar articles in displayed position, whereby the character of the articles in the compartments can be readily ascertained and further whereby a customer can readily see the character of the articles which are stored in the compartments.

A further object of the invention is to provide, in a manner as hereinafter set forth, a device for the purpose set forth including rotatably supported, horizontally disposed element having a refrigerant compartment and a series of communicating, readily accessible storage compartments surrounding the refrigerant compartment, readily accessible and formed in a manner to display the articles of merchandise contained therein.

A further object of the invention is to provide, in a manner as hereinafter set forth, a device for the purpose referred to for storing different articles of merchandise for dispensing by sale, and further including means for displaying articles of merchandise similar to the articles stored for dispensing purposes.

A further object of the invention is to provide, in a manner as hereinafter set forth, a device for the purpose referred to including a refrigerant compartment and a series of compartments surrounding the refrigerant compartment and adapted to have stored therein articles of merchandise for dispensing by sale, and with the device further including means whereby access can be readily had to the storage compartments, and with means

further to enable the supplying of a refrigerant, such as ice, to the refrigerant compartment and to enable the removable of the accumulated water from the refrigerant compartment.

Further objects of the invention are to provide, in a manner as hereinafter set forth, a rotatable, refrigerated, combined display and storage device for the purpose referred to which is simple in its construction and arrangement, strong, durable, attractive in appearance, thoroughly efficient in its use, conveniently rotated, enabling ready access to the articles of merchandise stored therein, readily assembled and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a front elevation of a horizontally disposed, rotatable refrigerated combined display and storage device in accordance with this invention.

Figure 2 is a view looking towards one end thereof.

Figure 3 is a longitudinal sectional view of the device.

Figure 4 is a view looking towards the other end thereof.

Figure 5 is a cross sectional view.

That element of the device which provides the refrigerant compartment or chamber and the storage compartments or chambers, is illustrated by way of example of polygonal cross section disposed horizontally and rotatably supported at its ends, but it is to be understood that the cross sectional contour of such element can be as desired, but preferably such element is set up as of polygonal cross section.

The device includes a rotatable shaft 1 which extends lengthwise of the compartment element 2 axially thereof, projects from each end of element 2, as at 3, 4 and has its ends 3, 4 mounted in the combined seat and retaining portions 5, 6 respectively, formed at the upper ends of the upstanding side portions 7, 8, respectively, which project from the ends 9, 10, respectively, of the rectangular base 11 of a stationary, skeleton supporting element 12. The length of the supporting element 12 is greater than the length of the element 2 and the latter is positioned between the side portions 7, 8, of element 12.

The shaft 1 is fixedly secured to element 2. Directly below the combined seat and retaining portion 5 of the upstanding side portion 7 of supporting element 12, the said side portion 7 is outset as at 13 to provide a clearance 14 for a purpose to be presently referred to. The side portions 7, 8 are substantially of inverted, yoke-shape and the combined seat and retaining portions 5, 6 are disposed centrally with respect to said side portions 7, 8. As shown, the supporting element 12 is constructed from lengths of wire of the desired gauge suitably connected together.

The element 2, centrally thereof, is formed with a hollow, cylindrical member 15, of the desired diameter and provided at one end with a closure 16 and at its other end with a closure 17. Preferably the member 15 is constructed of metal. The member 15 provides a refrigerant chamber 18. The closed ends 16, 17 of the member 15 have central openings 19 and bosses 20 on their inner faces which form continuations of the openings 19. The shaft 1 extends through the openings 19 and bosses 20 and is fixedly secured to the ends of member 15. The end 16 of member 15 is formed with an opening 21, to the wall of which is secured an outwardly directed, inclined, combined filling and discharge tube 22, provided at its outer end with a removable closure cap 23. The tube 22 is provided for filling compartment 18 with a refrigerant, such as ice and to enable the discharge of the water from chamber 18 after the ice has been melted. The clearance 14 is provided for the passage of the tube 22 when the element 2 is rotated.

The element 2 further includes a pair of end frames 24, 25 of polygonal contour and the former is formed with a series of quadrant-shaped openings 26 and the latter with a series of quadrant-shaped openings 27. Each frame is also formed with a central opening 28, which corresponds in contour to the shape of member 15 and the latter extends through said openings 28 and projects a substantial distance from the frames 24, 25, and these latter are fixedly secured to member 15 inwardly with respect to the ends 16, 17 of member 15.

Surrounding the member 15, seated there-

on and extending from frame 24 to frame 25 is a series of flat members 29 which correspond in number to the number of storage compartments and provide the bottom for such compartments. The members 29 are perforated as at 30 to enable the refrigerant to refrigerate or cool the articles within the storage compartments, and these latter compartments will be presently referred to.

The members 29 are of rectangular contour and the side edges thereof abut. The members 29 are secured to the frames 24, 25 and if desired, can be secured to the member 15. When the members 29 are arranged in abutting position the cross section thereof will be of polygonal contour.

The elements 2 further include a series of spaced, radially disposed partitions 31 of a length to extend from frame 24 to frame 25. The inner lengthwise edges of the partitions 31 overlap the joints between the side edges of the members 29. The outer longitudinal edges of the partitions 31 are spaced inwardly with respect to the outer edges of the frames 24, 25. The partitions 31 are secured to the frames 24, 25 and to the members 29.

Arranged between the frames 24, 25, secured to these latter and mounted upon the outer lengthwise edges of the partitions 31 are transparent closures 32 for the storage compartments. The number of closures 32 correspond to the number of storage compartments. The storage compartments are provided by the end frames 24, 25, members 29, partitions 31 and closures 32. As illustrated, the element 2 is set up with eight storage compartments and each of which gradually increases in width from its bottom 29 to a closure 32. The frames 24, 25 overlap the transparent closures 32, as indicated at 33. Retaining strips 34 are provided for the closures 32 and such strips 34 are arranged between the partitions 31.

One end wall of each compartment is provided by a transparent panel 35 suitably secured within the end frame 25. The other end wall of each compartment is provided by a hinged door 36 positioned in an opening 26, hinged to the frame 24, as at 37, and provided with a knob or handle piece 38. The door 36 snugly engages the wall of the opening 26. The openings 27 are closed by the transparent panel 35. The partitions 31 are formed with openings 39 for establishing communication between the storage compartments 40 whereby the passage of cool air can circulate through the compartments, and the articles within the compartments 40 cooled or refrigerated.

Each storage compartment is provided with means for supporting in displayed position articles similar to the articles which are stored within the compartment. The said means is so constructed as to permit of the displayed articles being refrigerated or

cooled, and said means further separates the displayed articles from the articles stored within the compartments and the said means is so arranged as to provide a display space at the outer portion of the storage compartments. The said means consists of a foraminous tray 41 which is detachably secured in position in any suitable manner, in proximity to the panel 32 but arranged a suitable distance inwardly with respect to panel 32 to provide a display space 42. As the tray 41 is foraminous, the articles supported thereby will be refrigerated or cooled as space 42 communicates with a storage compartment 40 rearwardly of tray 41. As the display space 42 will be filled with the articles which are to be displayed, the shifting of the articles is prevented when element 2 is rotated, and further the displayed articles are maintained separate from the stored articles by tray 41.

The doors 36 provide means whereby convenient access can be had to the compartments 40 for the purpose of removing stored articles when occasion requires.

It is thought the many advantages of a rotatable, refrigerated, combined display and storage device for the purpose referred to can be readily understood, and although the preferred embodiment of the invention is as illustrated and described, yet it is to be understood that changes in the details of construction can be had which will fall within the scope of the invention as claimed.

What I claim is:

1. A combined display and storage device comprising a longitudinally disposed element provided with a plurality of storage compartments having transparent outer walls, and a skeleton support having upstanding side portions provided with combined seat and retaining portions for rotatably supporting said element from the ends thereof between said upstanding side portions, said element further including a refrigerant compartment having extended from one end thereof a combined filling and discharge tube therefor, one of said upstanding side portions being outset to provide a clearance for said tube during the rotation of said element.

2. In a refrigerated, combined display and storage device, a horizontally disposed, cylindrical casing closed at each end and having one end provided with a normally closed, combined outlet and intake opening into the cylinder, said cylinder providing a refrigerant chamber, a supporting shaft extending through said chamber and projecting from each end of the cylinder, supporting means for the ends of said shaft arranged exteriorly of the ends of the cylinder, a pair of opposed frames secured upon the cylinder and arranged in spaced relation and each provided with a set of openings, hinged doors

for closing the openings in one of said frames, transparent panels for closing the openings in the other of said frames, apertured bottom members encompassing the outer periphery of said cylinder, radially disposed, apertured spaced partitions secured to said bottom members and in connection therewith providing radially disposed storage compartments, transparent front walls arranged between said partitions for closing said compartments, said hinged doors and transparent panels providing the end walls of said compartments.

3. A refrigerated, combined display and storage device comprising a horizontally disposed, rotatable casing closed at each end and providing a refrigerant receiving chamber, a pair of frames each mounted on and encompassing said cylinder at an end thereof and provided with spaced openings, flat, abutting, perforated bottom members seated on the outer periphery of the casing and extending from one frame to the other, radially disposed, spaced, apertured partitions seating on the bottom members and in connection with the latter and said frames providing storage compartments, transparent panels seated on said partitions, secured to said frames and closing the fronts of said compartments, hinged elements for closing the openings in one of said frames, transparent elements for closing the openings in the other of said frames, and a supporting shaft extending through said chamber and projecting from the ends of said casing.

In testimony whereof, I affix my signature hereto.

HUGH A. STOUT.
